LAURENCE Z. FORGUES, OF WOONSOCKET, RHODE ISLAND, ASSIGNOR OF
ONE-THIRD TO ARCHILAS R. BRILLON AND ONE-THIRD TO LOUIS M.
BAZINET, OF WOONSOCKET, RHODE ISLAND

LOOM-PICKER.

No. 836,073.

Specification of Letters Patent.

Patented Nov. 13, 1906.

Application filed August 24, 1905. Serial No. 275,520.

To all whom it may concern:

Be it known that I, LAURENCE Z. FORGUES, a citizen of the United States, and a resident of Woonsocket, in the county of Providence and State of Rhode Island, have invented certain new and useful Improvements in Loom-Pickers, of which the following is a specification.

This invention relates to improvements in loom-pickers, and has for its objects economy of construction and quickness in setting.

In all loom-pickers known to me there is a want of simplicity in the construction, which adds an element to the cost which it is desirable to eliminate. Furthermore, by doing away with the set-screw arrangement for clamping the head upon the staff the clamping operation is more quickly performed.

In the drawings which illustrate my invention, Figure 1 is a side elevation showing my picker-head mounted on a picker-staff. Fig. 2 is a section corresponding to line 2 2 of Fig. 1. Fig. 3 is a section corresponding to line 3 3 of Fig. 2. Figs. 4 and 5 are views of detached parts. Fig. 6 is a development of metal shell. Fig. 7 is a rear view of shell in its folded position.

1 is the picker-staff, and 2 the picker-shell. Picker-shell 2 is formed from a single piece of sheet metal and consists of the head 3, sides 4 5, side folders 6 6 7 7, and tailpieces 8 8, so cut as to bend into a shape suitable for clamping on staff 1.

The head 3 is provided with a hole 20 to receive the point of the shuttle, and within the shell between the hole and the staff 1 are layers of leather or other suitable material adapted to serve as a buffer. The head 3 of the shell is parallel to the picker-staff, thus making it possible to use leather pieces which are each of uniform thickness, and the inclosure formed by the sides 4 5 6 6 7 7 is of uniform width at front and back, so that a leather piece 21 at the back will fit precisely into the place of the leather piece 21 next the head or in any intermediate position. This makes it possible to shift the leathers gradually forward, inserting new ones at the back as the forward ones become worn. The side fold portions 6 6 7 7 bend over the top and bottom of the inclosure, holding the leathers, as clearly shown in Fig. 7. Not being fastened or otherwise tied together they are

free to be sprung apart by pulling the tailpieces 8 8 apart, thus separating the inclosure and permitting easy removal of leathers and insertion of fresh ones.

9 is a thrust-block formed with ears 10 10, which fit around the edges of the tailpieces 8, and is provided with a raised portion 11 on the side next the staff 1 and a slight depression 12 on the opposite side for purposes hereinafter described.

13 is a cam-shaped locking device having ears 14 14, adapted to lock in slots 15 15 in tailpieces 8 8, and an eccentrically-arranged central portion 16, adapted to press the thrust-block 9 firmly against the staff 1, and thereby force the raised portion 11 into the wood of the picker-staff.

By an inspection of Fig. 4 it will be noticed that this central portion 16 has not the exact outline of an eccentric, being ground away, as shown at x, and being provided with a flattened surface 17, which forms the locking-surface. The reason for this peculiar shape is to enable me to provide the flat locking-surface 17 without having a so-called "high point" at either side of same, thus giving a continually-increasing pressure as the locking device is turned into locked position. It is noticeable also that this shape makes it necessary to always turn in the same direction when locking, which is desirable.

18 is a perforation for the insertion of a turning-bar for locking the picker upon the staff 1. A bar can be permanently mounted in hole 18, if so desired; but I prefer not to do so.

In Figs. 1, 2, 3 I have shown an additional or supplemental locking means consisting of a spring-pressed pin 19, which enters depression 12 on the thrust-block 9 when in locked position; but this can be omitted without departing from the spirit of my invention.

Ears 14 14 are adapted to enter the large end of openings 15 15 and can then be moved to position in a well-known manner, the tailpieces 8 8 having sufficient flexibility to permit them to enter. When the tailpieces are thus spread apart, the entire head inclosure expands, the two sides separating along the line of cleavage between parts 7 and 6. (Clearly shown at the top and bottom of Fig. 7.) I therefore call the head "ex-

pansible," and the expansion thereof permits the easy removal of the buffer material contained within the inclosure and the easy rearrangement thereof or insertion of fresh pieces.

Having described my invention, what I claim is—

1. A picker-shell provided with tailpieces 8, a cam-shaped locking device adapted to be mounted in tailpieces 8 and having an eccentrically-arranged locking-face containing a flat portion 17, a spring-pressed pin mounted in said locking device, and a thrust-block 9 provided with a depression 12 for receiving said pin.

2. A picker-shell, having an expansible head inclosure for a buffer, and means to hold the shell upon a staff.

3. A picker-shell, having side pieces provided with flaps folded at top and bottom to form with the head-wall and picker-staff an inclosure for a buffer, said side pieces being extended rearward, and a fastening between the staff and the rearward portions of the side pieces, said side pieces being separable at the rear, whereby the walls of the inclosure may be sprung apart.

4. A picker-shell, having a head inclosure for a buffer, with tailpieces projecting from the sides of the inclosure, the walls of the inclosure being separable sidewise to expand the inclosure, and means to hold the shell upon a staff.

5. A picker-shell, having tailpieces pro-

jecting to the rear of the picker-staff; a removable pin, joining the tailpieces; and a cam arranged on the pin to engage the staff and fasten the picker-shell thereto.

6. A picker-shell, having tailpieces projecting to the rear of the picker-staff; a pin joining the tailpieces; and a cam arranged on the pin to engage the staff and bind the picker-shell thereto, said cam being rotatable upon the axis of the pin and having a hole for insertion of a key to rotate the same.

7. A picker-shell, having tailpieces projecting to the rear of the picker-staff; a pin joining the tailpieces; and a cam arranged on the pin to engage the staff and bind the picker-shell thereto, said cam being rotatable upon the axis of the pin, and means to latch the cam when in its binding position, said means comprising a flat surface on the cam arranged to engage a flat surface on the staff.

8. A picker-shell, having a head inclosure for holding a buffer, and means to fasten the shell upon a staff, the staff forming one wall of said inclosure, the front wall thereof being parallel to the staff, and the other walls being arranged to form the inclosure with uniform cross-section.

In testimony whereof I have affixed my signature in presence of two witnesses.

LAURENCE Z. FORGUES.
